DESIGN FOR AN ELECTRIC LANTERN

Judson S. Pixley, Astoria, N. Y.

Application October 25, 1937, Serial No. 72,408

Term of patent 14 years

To all whom it may concern:

Be it known that I, Judson S. Pixley, a citizen of the United States, residing at Astoria, county of Queens, and State of New York, have invented a new, original, and ornamental Design for an Electric Lantern, of which the following is a specification, reference being had to the accompanying drawing, forming part thereof.

Fig. 1 is a side elevational view of an electric lantern, showing my new design.

Fig. 2 is a top plan view of the same.

Fig. 3 is a bottom plan view of the same.

I claim:

The ornamental design for an electric lantern, substantially as shown.

JUDSON S. PIXLEY.
